CLAIM

The ornamental design for an optical imaging device, as shown and described.

DESCRIPTION

FIG. 1 is a perspective view of an optical imaging device showing our new design;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another right side elevation view thereof, shown in a position of use with an attached eye cap.

Broken lines shown immediately adjacent shaded areas represent the bounds of the claimed design and unclaimed portions of the optical imaging device. Broken lines in FIG. 9 showing an eye cap depict environmental subject matter only. All other broken lines are directed to unclaimed portions of the optical imaging device. All broken lines form no part of the claimed design.
